CLAIM

The ornamental design for a spray gun, as shown and described.

DESCRIPTION

FIG. 1 is a front, left side, top perspective view of a spray gun showing my new design;

FIG. 2 is a rear, right side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detailed view of the left side of the spray gun as generally indicated by the lead line in FIG. 1. The broken lines depict portions of the spray gun that form no part of the claimed design.

The dash dot dash broken lines indicate the cutoff boundaries for the enlarged detail views and forms no part of the claim.
